FLATIRON

Frank Schaefer, Kalamazoo, Mich.

Application May 13, 1931, Serial No. 537,081

1 Claim. (Cl. 68—26)

The main object of my invention is to provide means for ironing efficiently.

Another object of my invention is to provide means for supplying steam directly to the ironing surface.

A still further object of my invention is to provide a flatiron having means therein for generating steam and supplying such steam directly to the material being ironed or pressed.

Objects relating to details and economies of my invention will appear from the description to follow. The invention is defined and pointed out in the claim.

A structure which is a preferred embodiment of my invention is illustrated in the accompanying drawing, in which:

Fig. 1 is a perspective view of an electric flatiron constructed in accordance with my invention.

Fig. 2 is a bottom plan view of the flatiron shown in Fig. 1 having portions shown in cross section.

Fig. 3 is a cross sectional view of the flatiron taken on line 3—3 of Figs. 1 and 2, and

Fig. 4 is a view similar to Fig. 1 partially broken away of another modification.

Referring to the drawing, numeral 1 indicates an electric flatiron having a relatively heavy base 2, the bottom 3 of which constitutes a smoothing or ironing surface.

A water container 4 is mounted on the iron 1 between the brackets 5 which support the handle 6. The front part of the water container 4 is provided with an inlet connection 7 having a cap 8 mounted thereon. The cap 8 may be removed

when it is desired to fill the container 4 with a fresh supply of water or for connecting the inlet connection 7 to a source of steam when that is available.

The bottom of the water container 4 is also provided with an outlet connection 9 which is connected by means of tubing 10 to a conduit 11 formed in the base 2 of the iron 1 as shown.

The outlet connection 7 is provided with a valve 12 for controlling the amount of water which flows from the water container 4 through the tubing 10 to the conduit 11.

The conduit 11 preferably extends through the base 2 in the direction of the length thereof and communicates with a similar conduit 13 which extends through the base 2 at right angles to the conduit 11. A plurality of small openings 14 extend from the conduit 13 through the bottom 3 of the iron.

The conduit 13 is preferably formed by boring into the base of the iron and the entrance end of

the bore is preferably closed by a plug 15. The plug 15 may be removed when it is desired to clean or inspect the conduit 13.

The conduit 11 is similarly formed in the base by boring therethrough and the entrance end of the bore is provided with a packing gland 16 for connecting the lower end of the tubing 10 to the conduit 11.

The conduits 11 and 13 and particularly the conduit 11 form a generating chamber in the base 2 so that when water is slowly admitted through the tube 10 to the conduit 11, the heat of the base 2 caused by the electric heating element 17 causes the water to be immediately transformed into steam which escapes through the small openings 14 onto the surface of the material being ironed or pressed. The end of the tube 4 preferably terminates in a small jet not shown so that water may be admitted to the steam generating conduit 11 in small drops.

As pointed out above, the amount of water admitted to the steam generating conduit 11 may be controlled by the valve 12.

While I prefer to use a plurality of spaced openings 14 in the base 2 which communicate with the ironing surface 3, nevertheless one opening of suitable shape may be used in place thereof or a plurality of spaced slots 18 may be used as shown in Fig. 4. In this case, the slots 18 are arranged so as to be angularly related to the longitudinal axis of the base of the iron. With this arrangement, steam may be supplied to the surface of the material being pressed in an efficient manner.

In the past, it has been customary in using flatirons in household and commercial establishments to dampen the material to be pressed or by applying a damp cloth over the material to avoid burning the fiber thereof and to obtain the desired smooth and finished surface.

With my invention, the necessary dampness for the pressing is supplied to the material from the flatiron surface itself, the steam being generated within the iron or by connecting the iron to a suitable source of steam supply. Inasmuch as the openings or holes in the base of the iron communicate with the ironing surface, the steam is forced directly onto the material being ironed and there is no escape of steam from the circumference of the iron into the atmosphere.

The base of the iron is preferably of non-corrosive metal such as iron-chromium and similar alloys which are now easily available.

The diagonal slots in the base of the iron, as best illustrated by Fig. 4 of the drawing,

result in a very efficient delivery of the steam to the surface being ironed. This is brought about by virtue of the fact that the openings are kept open by the forward movement of the iron, and 5 furthermore, as the iron is moved forward in smoothing, portions of the ironing surface are uncovered to the slots or openings thereby insuring the dampening of the surface covered by the iron.

10 While I have illustrated and described preferred embodiments of my invention, it will be understood that various minor changes may be made in the construction thereof without de-

parting from the scope of my invention as expressed by my broader claim.

Having thus described my invention, what I claim as new and desire to secure by Letters Patent, is:

A flatiron base having an ironing surface with a plurality of parallel diagonally arranged slots for delivering steam to said ironing surface, said slots being disposed in diagonal relation to the longitudinal axis of said base and in a transverse belt relative to the direction of forward travel of the iron.
